Primary Examiner — Garth Rademaker*Assistant Examiner* — Katie Mroczka(74) *Attorney, Agent, or Firm* — Pillsbury Winthrop Shaw Pittman LLP(57) **CLAIM**

The ornamental design for an animal chew, as shown and described.

DESCRIPTION

FIG. 1 is a perspective view of an animal chew according to the present invention;

FIG. 2 is a front elevation view, to which the rear elevation and the top and bottom plan views are identical; and,

FIG. 3 is a right side elevation view, to which the left side elevation view is identical.

The broken lines in FIGS. 1-3 illustrate portions of the animal chew that form no part of the claimed design.
